(57) **CLAIM**

The ornamental design for the heat transfer appliance, as shown and described.

DESCRIPTION

FIG. 1 is a front elevation view of the heat transfer appliance showing our new design.

FIG. 2 is a top plan view of the heat transfer appliance.

FIG. 3 is a left side elevation view of the heat transfer appliance.

FIG. 4 is a right side elevation view of the heat transfer appliance.

FIG. 5 is a rear elevation view of the heat transfer appliance.

FIG. 6 is a bottom plan view of the heat transfer appliance.

FIG. 7 is a front perspective view of the heat transfer appliance; and,

FIG. 8 is a front perspective view of the heat transfer appliance attached to a standard water heater.

In the drawings, the broken lines depict environmental subject matter only and form no part of the claimed design.
